UNITED STATES PATENT OFFICE.

JOHN GEORGE BELL, OF IVEGILL, NEAR SOUTHWAITE, ENGLAND.

TIRE FOR VEHICLES.

No. 839,094.

Specification of Letters Patent.

Patented Dec. 25, 1908.

Application filed February 12, 1906. Serial No. 300,686.

To all whom it may concern:

Be it known that I, JOHN GEORGE BELL, a subject of the King of Great Britain and Ireland, residing at "Beacon Side," Ivecill, near 5 Southwaite, in the county of Cumberland, England, have invented a new and useful Improvement in Tires for Vehicles, of which the following is a specification.

This invention has reference to elastic tires 10 for vehicles, and is more particularly applicable to the wheels of cycles and motor-vehicles.

According to my invention I provide three bands of a springy or yielding nature, and 15 the outer and middle bands are preferably compound, as hereinafter described. Two of the bands are extensible and contractile—that is to say, their ends overlap and are free to slide over each other.

20 Referring to the accompanying drawings, Figure 1 is a front elevation, partly in section, of my improved tire; and Fig. 2, a plan thereof with the outer cover removed. Fig. 3 is an enlarged view of a portion of Fig. 1, and Figs. 4 and 5 plan views of the middle and inner bands, respectively. Fig. 6 is an enlarged cross-section of a portion of the tire.

In the drawings, A is the outer band, which 30 consists of four strips B C D F of spring-steel, and these are placed side by side circumferentially around the wheel, and G is a strip of spring-steel to cover the opening between the two middle strips of steel. These four strips of steel are held together sidewise and are 35 also kept a very slight distance apart from each other by means of lashings H, of string, canvas, tapes, or the like, the object of keeping them apart being to prevent squeaking through their edges grinding against each other. I provide also in some cases a thin 40 band of cork or other suitable material (not shown) to prevent this outer band coming into actual contact with and thereby cutting the outer cover I, which outer cover is similar to those ordinarily used with pneumatic 45 tires:

The middle band J is composed in much the same way as the outer band A, except that each strip J is made in four pieces with 50 overlapping ends K, which are wrapped round by flattened springs L, to which they are anchored by lugs E, so that when this middle band J is expanded these springs are compressed more or less, according to the 55 pressure brought to bear upon them.

M is a narrow strip similar to G of the outer

band, except that it has overlapping ends N, corresponding with those of the band J, and has sliding locks O. The object of this band M is to prevent the springs V, hereinafter described, from expanding too much.

The outer band A and the middle band J are connected together by means of spiral springs P, placed radially. There may be any suitable number of these, and one half of them are fixed at one side and the other half are fixed at the opposite side, as shown in Figs. 4 and 6, and they are so arranged that those on one side break joint with those on the other side, as I have found from experimental practice that this gives great resiliency.

The inner band Q consists of one strip, preferably thicker than the other two bands A and J, and it has only one overlapping portion R, which is provided with sliding locks S; but surrounding this band are two narrow strips of spring-steel T, having overlapping portions U, corresponding with those of the middle band J. These two strips U 80 and band J are connected by springs V; but these are stronger than springs P, so that they act to take up and distribute any excessive shock and also prove useful in the case of bad adjustment of the tire or in the 85 case of a heavy rider or load.

I prefer to provide distance-pieces W, preferably of cork or other suitable material, between the three bands, and these serve to prevent the radial springs being squashed 90 in case of emergency. In the rim Y of the wheel itself I provide outwardly-extending screws X, and when these are screwed outward they press upon the inner band and expand it, thus putting all the parts into 95 tension more or less, as required, it being understood that the outer cover I has been placed in position over the bands while they were in their contracted state.

What I do claim as my invention, and desire to secure by Letters Patent of the 100 United States, is—

1. An elastic tire for vehicles comprising three bands of a springy or yielding nature the outer band being composed of four strips 105 lashed together without any overlapping ends and a narrow strip covering the opening between the two middle strips, a middle band similar to the outer band but overlapping at several points in the circumference, and an inner band, said middle band being connected by radial springs to the outer and 110

inner bands respectively, the whole being enclosed in an outer cover substantially as described.

2. In an elastic tire the combination with an outer continuous band, of a middle overlapping band having flattened springs embracing such overlapping portions and being anchored thereto, a narrow strip surrounding such band having also overlapping portions anchored in sliding locks, and radial springs connecting both bands substantially as set forth.

3. In an elastic tire the combination with an outer and middle band, of an inner single band overlapping at one point, two narrow bands surrounding such single band and having overlapping portions corresponding with those of the middle band, and radial springs

connecting the two narrow bands with the middle band substantially as set forth. 20

4. An elastic tire consisting of an outer band, middle and inner bands, springs connecting such bands, distance-pieces between such bands and adjusting-screws for putting the parts in tension all of which being enclosed in an outer cover substantially as described and shown in the accompanying drawings. 25

In testimony whereof I have signed my name to this specification in the presence of 30 two subscribing witnesses.

JOHN GEORGE BELL.
